United States Patent Office.

JOHN H. PARK, OF WHITE HOUSE, NEW JERSEY.

Letters Patent No. 77,648, dated May 5, 1868; antedated April 24, 1868.

IMPROVEMENT IN BAG-HOLDERS.

The Schedule referred to in these Letters Patent and making part of the same.

TO ALL WHOM IT MAY CONCERN:

Be it known that I, JOHN H. PARK, of White House, in the county of Hunterdon, and in the State of New Jersey, have invented certain new and useful Improvements in Bag-Holders; and do hereby declare that the following is a full, clear, and exact description thereof, reference being had to the accompanying drawings, and to the letters of reference marked thereon, making a part of this specification.

In the annexed drawings, A represents an upright bar, which is suitably notched, *zz*, on its back, and connected to a base or platform, A'.

B represents a square or other suitably-shaped block, provided with an opening in its centre, by which means it is passed over the standard A. Pivoted to the rear upper face of the block B are two eccentric-shaped levers, D D, of metal, and so constructed as to form a hoop at the front, D'. It will be seen that these levers are bent so as to extend to the front and to the rear of the standard A, and that they cross each other at the rear of said standard, where they are pivoted at *z*, so as to operate somewhat in the manner of a pair of shears. *aa* represent two springs, which are secured to the sides of the block B, and lie against the inner sides of the handle portions of the levers D D, for the purpose of forcing the hoop to its normal position after being contracted. The front of the levers, in the rear of the hoop D', is so bent as to form small square-shaped loops (see *i*) for supporting the back part of the bag. These loops may or may not be formed, as preferred. *e* represents a rack-bar, which is connected to the rear end of one of the levers, and is intended to catch over the opposite one, for connecting them, and securing the hoop D' in the condition required.

E represents a curved metal plate, attached to the forward part of the block B, for strengthening this block and assisting in the connection of the bag.

By means of the levers D D it will readily be seen that the hoop D', where the bag is to be attached by means of the pins *zz*, can be adjusted to suit the size of the mouth of the bag to be filled, and held in the position by the rack-bar *e*. This bag-holder can be adjusted to suit the height as well as the circumference of the bag.

C represents a wedge, which is set into a small groove on the front of the standard A, and passed into an opening in the block B, for securing the said block upon any desired notch on the standard.

Having thus fully described my invention, what I claim as new, and desire to secure by Letters Patent, is—

The metallic levers D D, pivoted as described, and forming a hoop at the forward end, when provided with rack-bar *e*, and used in connection with the block B, with its springs *aa*, all constructed and operating in the manner and for the purposes set forth.

In testimony that I claim the foregoing, I have hereunto set my hand, this 22d day of July, 1867.

JOHN H. PARK.
